UNITED STATES PATENT OFFICE.

FREDERICK W. WOOD, OF LOS ANGELES, CALIFORNIA.

CASE FOR DISK RECORDS FOR PHONOGRAHS.

1,018,689.

Specification of Letters Patent. Patented Feb. 27, 1912.

Application filed November 6, 1911. Serial No. 658,910.

To all whom it may concern:

Be it known that I, FREDERICK W. Wood, a citizen of the United States, residing at Los Angeles, in the county of Los Angeles 5 and State of California, have invented a new and useful Improvement in Cases for Disk Records for Phonographs, of which the following is a specification.

This invention relates to a case for holding disk records such as used in phonographs, and the main object of the invention is to provide an improved construction of the case, whereby the cost of manufacture of the case is reduced to a minimum.

Other objects of the invention will appear hereinafter.

The accompanying drawings illustrate an embodiment of the invention, and referring thereto: Figure 1 is a vertical section of a 20 phonograph case constructed according to my invention. Fig. 2 is a section on line x^2-x^2 in Fig. 1. Fig. 3 is a section on line x^3-x^3 in Fig. 2. Fig. 4 is a perspective of the portions adjacent to the joint between 25 the vertical and horizontal bars for separating the disks. Fig. 5 is a perspective of one of the buttons for such rods for ejecting the disks. Fig. 6 is a longitudinal section of a button.

The case is provided with bottom 1, sides 2, back 3, and top member 4. The front of the case is provided with a series of vertical bars 5, arranged in parallelism and spaced apart sufficiently for insertion of the record 35 disks between them. Horizontal spacing bars 7 extend rearwardly from the vertical bars 5, being connected with said vertical bars at their forward ends and being supported at their rear ends by engagement between 40 horizontal splines or strips 8 which are inserted in recesses 9, cut in vertical ribs 10 formed on the rear wall 3, said vertical ribs 10 being interposed between the successive horizontal bars 7 and spacing the 45 same apart. In order to connect the horizontal bar 7 with the vertical bar 5 at the front of the case in such manner as to provide a flush joint and with minimum expense, I use the joint shown in Fig. 4, the 50 vertical bar 5 and horizontal bar 7 having slots 11 and 12 respectively and a fastener 13 consisting of a strip of metal bent in U-shape being inserted in said slots 11 and 12 and fitting tightly the respective bars 5 and 55 7 so as to hold the two bars in the same plane. The bars 5 and 7 may be cut away

as at 14 and 15, to enable the fastener 13 to lie flush with the surface of the bars. The case and spacing bars are preferably of wood, the above described connections giving 60 a compact arrangement of the spacing bars, allowing said bars to be made quite thin and light, and facilitating the assembling thereof.

16 designates a brushing surface which 65 may be provided on the edges of the vertical bars.

An ejector lever 17 is provided for each disk, said ejector levers being pivotally mounted on a shaft or rod 18 extending 70 across the case from side to side, and arranged near the back of the case in the plane of the respective slots back at the front of the case. Springs 19 are mounted on the back of the case for engaging said 75 ejector levers to hold the same in normal position and push rods 20 engage with the upper end of said levers to operate the same for ejecting the record disks. Said push rods near their forward ends slide through 80 suitable guide perforations 21 in the front of the case and are provided at their forward ends with buttons or heads 22, said buttons or heads being numbered in correspondence with the number of the record. 85 Each button 22 is provided with a cylindrical recess 23 in its front end, said recess having an annular channel 24 extending out into the wall of the recess, so that the number disk 25 and the transparent cover 90 disk 26 therefor, may be pressed into said channel, said disks being of slightly greater diameter than said recess, so that they are snapped out into the annular channel aforesaid and are thereby retained in place. 95

What I claim is:

1. In a record case, the combination with vertical front bars spaced apart to form slots, of horizontal spacing bars extending in the plane of said front bars, and connected to said front bars at their forward ends, and means for supporting the rear ends of said horizontal spacing bars, each horizontal bar and the corresponding vertical bar having opposite slots and being connected by a 100 fastener extending in said slots, said fastener being bent in U-shape to engage said bars.

2. In a record case, the combination with vertical front bars spaced apart to form slots, of horizontal spacing bars extending 110 in the plane of said front bars, and connected to said front bars at their forward ends,

and means for supporting the rear ends of said horizontal spacing bars, each horizontal bar and the corresponding vertical bar having opposite slots and being connected by a fastener extending in said slots, said fastener being bent in U-shape to engage said bars, said fastener being embedded in said bars, so as to lie flush therewith.

In testimony whereof, I have hereunto set my hand at Los Angeles, California, this 10 26th day of October, 1911.

FREDERICK W. WOOD.

In presence of—

ARTHUR P. KNIGHT,
GLADYS RUSSELL.
